UNITED STATES PATENT OFFICE.

FRITZ MAYER, OF ULM, GERMANY, ASSIGNOR TO THE FIRM C. D. MAGIRUS A.-G., OF ULM-ON-THE-DANUBE, WURTTEMBERG, GERMANY.

MAST OR SUPPORT FOR LIFE-SAVING APPARATUS.

Application filed August 1, 1921. Serial No. 488,976.

To all whom it may concern:

Be it known that I, FRITZ MAYER, a citizen of the German Republic, and a resident of Ulm-on-the-Danube, Wurttemberg, Germany, have invented certain new and useful Improvements in Masts or Supports for Life-Saving Apparatus (for which I have filed an application in Germany, July 10, 1915), of which the following is a specification.

This invention relates to a mast or support for life-saving apparatus and the like which is capable of being inclined as desired and is telescopically extensible and the movements of which may be executed with varying velocity. The masts already known provided with a head search-light are as a rule operated in such a manner that the elevation and extension of the mast take place uniformly and at the same time. In view of this the change from one speed to another must take place gradually and with due regard for the effect of the weight of the mass of the search-light at the head of the mast so that the mast, while being erected, during the first period of its inclination, and so long as its position deviates little from the horizontal, is moved slowly, the speed of movement being not increased till shortly before the vertical position is reached.

In comparison with this known apparatus, the present invention has for its object to introduce automatic changes of speed at the appropriate moments, these being under control of the operator. In this way the risk of endangering the stability of the apparatus through inattention or mistakes in driving is avoided. A further important feature is that this change in speed need not take place gradually but may be effected suddenly and in a moment so that an appreciable saving of time is brought about. In the drawings, the essential features of the invention are represented in a practical construction by way of example.

Fig. 1 is a side elevation of the complete mechanism, the mast or rescue ladder being in its telescoped or lowered position.

Figs. 2 and 3 illustrate the different mechanisms provided for the operation of the ladder, as seen in front elevation and in plan respectively.

Fig. 4 is a side elevation of various elements of the driving-mechanism.

In Figs. 3, 5 and 6 the mechanism provided for effecting the changes in speed of the movements of the ladder is represented.

Figs. 5 and 6 give the outlines of the mechanism at different stages of its operation.

Fig. 7 is a front-view (partly in dotted lines to show some otherwise covered members of the mechanism) of the complete actuating mechanism, or, in other words, a combination of the parts shown diagrammatically in the lefthand portion of Figure 1 with the details illustrated in the Figures 8-12, the whole being drawn on a greatly increased scale in proportion to Fig. 1.

Fig. 8 is a vertical section through a casing containing several gears, these latter being shown in side-view and the plan of section lying at right angles to Fig. 7, i. e. parallelly to the longer edges of the sheet. Fig. 9 is a horizontal section through one (58) of these gears, viz. the lowest of Fig. 8, and being drawn on a still larger scale. Fig. 10 is a horizontal section through one of the coupling chambers (60) provided in said casing (Fig. 8). Fig. 11 is a similar section through another such chamber (61), and Fig. 12 is also such a section (through chamber 63); the scale of these three figures is the same as that of Fig. 8.

For the operation of the apparatus the motors chosen may be of any kind which may be started and stopped directly or by means of a control-gear (fluid transmission reversing gear or the like). The motors and the associated reversing gear 2 are mounted upon the carrying platform 1 of the ladder. From the gear project the driving shafts 3, 4, one of which 3 serves to elevate or incline the mast or ladder 6, which is mounted in bearings 5. The driving power is transmitted by toothed-wheels 7, 8, and a set of bevel wheels 9 and 10 (Fig. 7) to the driving spindle 11. On the latter is engaged a nut 12, which, with a tube 13 is pivoted on bolts or pins 14 on the lower part of the ladder. By rotation of the spindle 11, the nut 12 is caused to travel along the same and the ladder is turned about the axis 5, that is, it is elevated or inclined. Round the shaft 4, which

effects the extension and retraction of the mast or ladder, are led belts or cables 16 and 17 for the rotation of the drum 18. The control of the gear 2 is accomplished by means of the cocks 19, 20, by which the fluid is permitted to pass as desired to the points at which it is required for the operation of the gear for operating the driving shafts 3 and 4.

10 Concerning now the change-gears housed in the casing 2, this latter contains a plurality of friction couplings which are to be actuated by a liquid under pressure and are singly enclosed in pressure-tight chambers 15 (Fig. 8). The couplings are supported on three shafts, as described in detail hereinafter.

One of these shafts is the shaft 50, Figs. 8-10, which is one of the members for erecting the mast, as well as for tilting it. It has affixed to it a worm 51 which meshes with a worm-wheel 53 affixed to a shaft 52 having secured to it, besides said worm-wheel, a bevel-wheel 9 meshing with another 25 bevel-wheel 10 keyed to the erection spindle 11. This spindle is threaded and is encompassed at its other end by a nut 12, Fig. 1, affixed to the adjacent end of a tube 13 hinged with its other end to a bolt or pivot 30 14 forming a member of the lower structure of the ladder. Corresponding to the direction of rotation of the spindle 11 the nut passes along this latter in the one or the other direction, and the lower structure of 35 the ladder is turned upon the axle 5, whereby the ladder is erected or tilted, as the case may be.

The shaft 50 extends downwardly into a chamber 54 which contains the gear for the 40 quick erection of the ladder. This gear consists of a cog-wheel 55 affixed to the shaft 50, of two cogged disks 58 58 provided with concentric grooves on their adjacent sides, and of a friction disk 57 having concentric feathers engaging said 45 grooves. The disk 57 is secured to a shaft 56 upon which the disks 58 are rotatably mounted.

Similar friction couplings are provided 50 in chambers 59, 60 and 61, located in the upper half of the casing 2, and in chambers 62 and 63 located left-hand from the shaft 50. The rotary members housed in the chamber 59 consist of two cogged coupling 55 disks 64 shaped like the disks 58 and having also an intermediate disk with concentric feathers, like 57, between them, of a cog-wheel 65 secured to a shaft 56. This coupling serves for the slow erection of the 60 ladder. The coupling housed in the chamber 60 serves for the slow tilting of the ladder. It consists of the cogged disks 68 and the cog-wheel 67, also of a feather-disk like 57 which engages the grooves of the 65 disks 68. The disks 64 and 68 are rotatably

supported upon the shaft 50, and the respective feathered disks are secured to this shaft, whereas the cog-wheels 65 and 67 are affixed to the shaft 56. The members contained in the chamber 61 serve for the quick 70 tilting of the ladder and consist of two cogged friction disks 70, a feathered disk located between them, and a cog-wheel 71. The disks 70 are secured to the shaft 56, and the wheel 71 is secured to the shaft 50; 75 it meshes, however, not directly with the cogged disks 70, but an intermediate cog-wheel 72 (Fig. 11) is provided to reverse the direction of rotation. The same is the case with the cogged disks 68 and the cog-wheel 67; a cog-wheel 69 (Fig. 10) is inserted between them to reverse the direction of rotation, as necessary in view of the reserve movement the ladder shall make.

Finally, concerning the chambers and the 85 friction couplings, there are two neighbouring chambers 62 and 63 containing grooved friction disks 74 and 77 and cog-wheels 73 and 76, which latter are secured to the shaft 56, whereas the feathered disks between the 90 friction disks are affixed to a shaft 75 having at its upper end a bevel-wheel 82. Just as in Figures 10 and 11, the cog-wheel 76 meshes not directly with the cogged friction disks, but an intermediate wheel 78 95 (Fig. 12) reverses the direction of rotation. The coupling members contained in the chamber 62 serve for the extension of the ladder, and the coupling members contained in the chamber 63 serve for the telescoping of it.

The shaft 56 is the main shaft of the casing 2. Power is transmitted to it from the motor of the vehicle by the mediation of a shaft 81 and two bevel-wheels 80 and 79, 105 Fig. 8. The shaft 81 may be disconnected from the motor by any suitable means.

To the shaft 52 is affixed a cog-wheel 8 gearing with a similar wheel 7 (Figs. 1 and 8) secured to a control shaft 3 having a cam 110 a^1 (Figs. 2 and 7) affixed to it. Oppositely to this cam is a similar cam b^1 Figs. 2 and 7 affixed to a control shaft 4 geared to the shaft 75 (Fig. 8) by the mediation of the bevel-wheel 82, another bevel-wheel 83, and 115 two cog-wheels 84 and 85. The wheels 83 and 84 are affixed to a shaft 4 a having also a rope-pulley secured to it, and two endless ropes 16 and 17 (Fig. 1) drive a rope drum 18 whereby extending the ladder and 120 telescoping it is effected.

The driving fluid, for instance oil, is put under pressure by means of the pump 92, Fig. 7, which sucks the oil through a tube 93 from the store space formed by the lower portion of the casing 2, below the coupling chambers. The oil is then forced through pipes 94 and 95 to the control cocks 19 and 20 (Figs. 1 and 7) from which it is conducted to the several coupling chambers in 130

a manner hereinafter described. The oil returning from these chambers passes again through the control cocks and then through discharge tubes 96 and 97 back into the bottom space of the casing 2.

The control cocks and the coupling chambers are connected with each other by pipes 86, 87, 88, 90 and 91 (Fig. 7). The oil getting into a coupling chamber, for instance 54, Fig. 9 presses the loose outer disks (58) against the intermediate disk (57) which is rotated by the respective shaft (56) so that then also the outer disks are rotated, whereby the cog-wheel (55) that meshes with these disks and the shaft having the cog-wheel affixed to it are rotated, too. If, thereafter, the supply of oil under pressure is interrupted, the cogged friction disks are no longer pressed against the intermediate disk and the transmission of the rotary motion, therefore, ceases. Supplying the oil to the coupling chambers and discharging it from the same is effected by turning the control cocks in the one or the other direction. The cock plugs have levers 22 (Fig. 1) affixed to them; each lever forms a kind of hand which co-operates with a scale 23 with aid of which the proper position of each plug may be determined.

The cams a^1 and b^1 co-operate with curved double-armed levers 24 and 25 which are loosely supported upon bolts or pivots 26 and have each a small anti-friction roll 27 at the end where the respective cam acts. The other ends of the levers are connected with each other by a double-armed lever 28 having slots 29 through which pass bolts by which this lever is coupled with the levers 24 and 25. The lever 28 is supported by a vertical bar 30 guided in a projection of the casing 2 and having at its lower end a transverse piece 31 which may be adjusted in height, as shown in Figure 7, where the lower end of the bar 30 is threaded and a nut is provided for the adjusting purpose.

The object of this arrangement and combination of parts is to limit the movement of the control plugs, as well as to close the control cocks at certain times. The transverse piece 31 co-operates with two eccentrically arranged projections attached to the plugs of the cocks by pins or bolts 32. At the ends of the transverse piece are screws 33 which may be adjusted in it so that the moment of contact with the projections mentioned may be determined as required. The movements of the ladder, as well as its several positions, depend upon the position of the control cocks. If the ladder lies horizontally as in Figure 2, the two cocks are in their zero position, into which they are moved by certain members which do not form parts of this invention.

The other positions of the cock-plugs are indicated by radial lines. The lines R R'

(Fig. 2) at the cock 19 indicate the positions the plug is to have when the ladder is to be erected. The oil under pressure is then led either through the pipe 86 (Fig. 7) to the chamber 54 or through the pipe 87 to 70 the chamber 59, depending on whether the ladder is to be quickly or slowly erected. To tilt the ladder, the plug of the cock 19 is turned into the position N, or N' respectively, when the oil under pressure will be 75 led through the pipe 88 to the chamber 60 or through the pipe 89 to the chamber 61, also depending on whether the motion is to take place slowly or quickly. If the plug of the cock 20 is in the position R' or in the position N' (Fig. 2), the movements of the ladder, i. e., the erecting and the tilting, proceed with greater speed. As to the plug of the cock 20, A indicates that position in 80 which the ladder is extended which is effected by conducting the oil under pressure through the pipe 90 into the chamber 62, whereas in the position E of the plug the ladder is telescoped which is effected by conducting the oil through the pipe 91 into the chamber 63. The automatic control of the cocks and also the limitation of their movements is effected both during the elevation and during the lowering of the ladder. 85

When the ladder has been partially erected and the cam a^1 has rotated to a certain degree in the direction R, the movement of extension ceases at a definite moment, as the motion of the lever 25 resulting from the form of the cam b^1 effects the lifting of the transverse rod 31 by which the cock 20 is brought to the zero-position. Only when further elevation has taken place and the cam a^1 has rotated further in the direction R, does the transverse rod again move 100 downwards, permitting the cock 20 to move in the direction A to enable the ladder to be further extended. This cycle of operation, of course, takes place in the reverse order when the ladder is being retracted in 105 a partially elevated position. It follows also that any further downward inclination of the ladder or mast is possible only if it has been or is sufficiently retracted as the result of the cam b^1 turning in the direction E and the transverse rod 31 falling on the movement of the lever 25, so that the cock 110 115 120 125 130 135 140 145 150 155 160 165 170 175 180 185 190 195 200 205 210 215 220 225 230 235 240 245 250 255 260 cam 34 intended for the purpose and which is mounted on the shaft 4 of the cam 31. The cam 34 is furnished for a portion of its circumference with a double curved guiding surface formed for a certain distance about a common centre, (Fig. 5) while the remaining portion is open. It serves to guide the roller 35 of a bell crank lever 36 pivotally mounted on the axis pin 26, and which by means of the link 37 is connected with a second bell-crank lever 38 carried by an axis pin 26'. From the lateral arm of the bell-crank lever 38 extends a rod 39 which is connected with the crank pin 32 of the cock 19. The connection of the lever 38, with the link 37 is effected by means of a longitudinal slot 40. When, for example, the ladder is simultaneously extended and elevated with increased speed, as is often the case with a view to saving time, then when the extension has been partly effected or, in other words, when the roller 35 has reached the depressed cam surface concentric with the centre of the cam 34, the lever system 36, 37, 38, 39 is constrained to move from the position indicated by the full lines in Figure 5 into that indicated by the dotted lines and to advance the cock 19 from the position R¹ to the position R whereby the movement of elevation is slackened. Thereafter the cock 19 may be set to the zero position to stop the elevation or in the event of the elevation being completed, it is brought automatically to the zero-position. The position of the lever system as in Fig. 6, is then that indicated by the full lines. If, on the other hand, it is desired to depress the ladder, then this may be effected during the movement of the roller 35 in the concentric curved cam path with only a reduced speed as the upper end of the lever 38 can only swing to the left as far as the extremity of the slot 40, to which corresponds the short displacement of the cock from zero to N. When, however, the roller 35 leaves the concentric cam path, for example, when the telescoping of the ladder has advanced to a certain stage, then the cock 19 may without constraint be turned into the position N¹,

and the last stage of the depression proceeds at increased speed. The lever system then occupies the position indicated in dotted lines in Fig. 6. By means of inclined surfaces at the exit and entry portions of the curved cam path, the roller 35 may be constrained to move continuously as desired.

Having thus particularly described the nature of my invention, what I claim as new and desire to secure by Letters Patent of the United States is:

1. A carrier for life-saving apparatus, comprising, in combination, means for erecting and for pushing out the carrier proper, means for controlling and operating said erecting and pushing out means, and a cam disk connected with the controlling means of said pushing out means to be operated thereby, and being connected to the controlling means of said erecting means by a lever combination connecting said cam disk with the controlling means of said erecting means, said lever combination being adapted to effect an automatic adjustment of the controlling of the said erecting gear and thereby a change of speed in the erecting movement, as set forth.

2. A carrier for life-saving apparatus, comprising, in combination, means for erecting and for pushing out the carrier proper, means for controlling and operating said first-mentioned means, a cam disk connected with said controlling means, a lever combination adapted to this connection, as well as an automatic adjustment of the controlling means of said erecting gear and thereby a change of speed in the erecting movement, and a longitudinal slot provided for the pivotal connection of two certain levers of said lever combination, said longitudinal slot being arranged at the end of one of said levers and permitting a free adjustment of the controlling means for the erecting gear, without influencing the other parts of the apparatus.

In testimony whereof I affix my signature.

FRITZ MAYER.
